US Office Action dated Oct. 15, 2014, from related U.S. Appl. No. 29/477,431.

Primary Examiner — Cynthia Underwood(74) *Attorney, Agent, or Firm* — Foley & Larnder LLP(57) **CLAIM**

We claim the ornamental design for a case for electronic pad, as shown and described.

DESCRIPTION

FIG. 1 is a perspective view of a case for electronic pad of the claimed design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines in the drawings are for illustrative purposes only and form no part of the claimed design.
